STATIONARY GRIP ATTACHMENT FOR
SPINNING SOCKET WRENCHES

George J. Houston, Scranton, Pa.

Application July 19, 1948, Serial No. 39,483

1 Claim. (Cl. 81—177)

1

This invention relates to a holder for a socket wrench of the type having a plurality of sockets on arms in the form of a cross, wherein the wrench is held by one socket with one hand while it is spun around by sockets on laterally disposed arms.

The purpose of this invention is to provide a holder in the form of a top that is adapted to hold the wrench from one point without being rigidly connected to the wrench.

Socket wrenches of this type are used to tighten and loosen nuts or cap screws of motor vehicle wheels when repairing tires, and after the nut or screw is loose, the wrench is spun to continue the unscrewing movement. With the usual type of wrench, it is difficult to hold the outer end or socket as the wrench is spun. With this thought in mind, this invention contemplates a cap or holder adapted to cover the socket with a point that fits into the socket, wherein the socket may be held by a hand without direct contact between the hand and wrench.

The object of this invention is, therefore, to provide means for forming a holder or stationary grip attachment for socket wrenches, having arms in the form of a cross, wherein the wrench may readily be held as it is spun to tighten or loosen a nut or screw.

Another object of this invention is to provide a holder or stationary grip attachment for socket wrenches having laterally disposed arms, that is adapted to be used on wrenches and sockets of different sizes.

A further object of the invention is to provide a holder, adapted to be installed on the end of a wrench having laterally disposed arms, which is of a simple and economical construction.

With these and other objects and advantages in view, the invention consists of the new and useful combination, construction, and arrangement of parts as hereinafter more fully described, set forth in the claim appended hereto, and disclosed in the accompanying drawings forming part hereof, wherein:

Figure 1 is a side view in elevation of a motor vehicle wheel and shows a wrench having the holder or stationary grip attachment on one of the sockets thereon positioned on one of the bolts thereof.

Figure 2 is a view showing an end elevation of the wheel, with the wrench and holder positioned on one of the bolts thereof.

Figure 3 is an elevational view looking into the open end of the holder or stationary grip attachment.

Figure 4 is a longitudinal section through the holder taken on line 4—4 of Figure 2, showing the point of the holder in a socket of a wrench, the end of which is also shown in section.

Referring now to the drawings, wherein like reference characters denote corresponding parts, the holder of this invention includes a tubular casing 10, having a head 11, with a point 12 permanently mounted in the head.

2

The casing 10 is comparatively small, being adapted to be held comfortably in one's hand, and the head 11 may be welded to one end of the casing, or may be formed of material such as babbit that may be cast in the end of the casing, with a base 13 of the point 12 cast therein. The base of the point may also be welded in the head, or secured therein in any manner or by any means.

10 With the parts arranged in this manner, the holder may be positioned on a socket 14 of a wrench 15, and with the wrench positioned over the head of a cap screw 16, the wrench may be spun about the center by the laterally disposed arms 17, and with the socket 14 positioned in the holder 10, the outer end of the wrench may be held in alignment without attempting to hold the revolving socket or arm of the wrench directly in the hand.

20 It will be understood that the holder or stationary grip attachment may be made of metal, plastic, or any suitable material.

25 It will also be understood that modifications may be made in the design and arrangement of the parts without departing from the spirit of the invention.

What is claimed is:

30 A bearing and grip device for cross-arm type wrenches having outwardly disposed lug-engaging sockets on the ends of the arms and said sockets having depressed bottom portions; said device comprising a tubular casing of larger inside diameter than the external diameter of any one of said sockets, a head member rigidly mounted in one end of the tubular casing, a pointed rod positioned inside of the tubular casing and in concentric relation thereto, and said pointed rod being rigidly secured at its non-pointed end to said head member, the pointed end of said rod being engageable with the depressed bottom portion of each of said sockets to thereby hold said tubular casing in surrounding and spaced relation to the socket in which the point is positioned, and thereby form a bearing 35 for said wrench when an opposite socket is applied to a bolt head and said wrench is spun about an axis extended through the socket in which the point is positioned, and said opposite socket, said casing forming a stationary grip for said socket 40 in which the point is positioned, during such spinning movement of the wrench.

GEORGE J. HOUSTON.
